LIGHT SIGNAL UNIT

Oscar S. Field, Rochester, N. Y., assignor to
General Railway Signal Company, Rochester,
N. Y.

Application March 14, 1931. Serial No. 522,713

3 Claims. (Cl. 240—44.26)

This invention relates to light signals for railway signalling purposes, and more particularly to means for focusing a lamp in such signals.

It is very necessary for light signals used in railway signalling to have an efficient light projecting system as the energy consumption must be small and the signal indication must be visible at a comparatively long range even under unfavorable light conditions. In railway signalling, 5 the use of reflectors or curved mirrors to increase the efficiency of a light projecting unit is objectionable because of the false indication which may be produced by an external light being reflected by the mirrors and thereby giving the 10 appearance of a lighted signal. However, the efficiency of such units can be increased by the proper arrangement of lenses and by the proper location of the light source with respect to these lenses.

15 It is common practice to use incandescent electric lamps having a concentrated filament in such light projecting units and these lamps are adjusted during the assembly of the unit by the aid of a dark room or a photometric means so that the filament is in the proper focal point. 20 However, when these light signals are in service, it is necessary from time to time to replace these lamps and the new filament must necessarily occupy the same position as the one it replaced. 25 Commercially manufactured electric lamps usually differ slightly in the positioning of the filament with respect to the base of the lamp and consequently the filament of a replaced lamp rarely occupies the right focal point. An adjustment of the replaced lamp can be accomplished 30 by observing the appearance of the signal from a distance but this method is obviously awkward and very inaccurate.

In view of the above facts, it is proposed in 40 accordance with this invention to provide a light projecting unit which permits adjustment of the lamp socket relative to the lens of the unit in such a manner that the lamp filament can be accurately located at the focal point of the lens. 45 It is also proposed to provide means in the light projecting unit whereby the location of a correctly positioned filament is recorded to facilitate in properly adjusting future lamp installations.

50 Other objects, purposes and characteristic features of the invention will appear as the description thereof progresses, during which reference will be made to the accompanying drawings, in which:—

55 Fig. 1 is a rear elevation of a proposed light

projecting unit having the rear cover and light shield removed.

Fig. 2 is a sectional view substantially on line 2—2 of Fig. 1 viewed in the direction of the arrows.

Fig. 3 is a top view of the same unit with parts removed to show the structure of the unit.

Fig. 4 is a diagrammatical illustration of the focusing means.

Fig. 5 is an enlarged view of an adjustable light emitting plate included on the proposed signal unit.

Fig. 6 is a perspective view on an enlarged scale, of the units, with parts broken away.

The particular type of railway signal employing the proposed light projecting unit is usually made up of a plurality of such units which are arranged either by position or by employing various colored lenses to produce the desired signal indications. Such signals may differ 70 greatly in their arrangement of light projecting units according to the particular application but all of such component units are of substantially the same construction and are interchangeable except for the particular colored lenses which 75 may be employed to distinguish the indication.

The light projecting unit illustrated consists essentially of a frame F holding an inner lens L¹ and an outer lens L² of the conventional doublet combination. These lenses are securely held in 85 annular rabbets in the frame F and outside of the outer lens L² a prism deflecting glass L³ is similarly held which is employed to diffuse or horizontally spread the signal light to meet the particular indication needs.

A hollow backwardly extending portion F¹ of the frame F carries a lamp supporting rod 1 threaded therein and locked by a nut 2 and to further prevent turning it is secured by a pin (not shown). This rod 1 is also threaded at its free 95 end and carries a lamp socket support 3 which is retained against knurled nuts 4 and 5 by a compression spring 6. The support 3 receives the rod 1 through a split bushing thereby permitting an angular and a vertical adjustment thereabout. The support 3 can then be secured in its adjusted 100 position by a bolt 7 and nut 8 which clamps the split bushing about the rod 1.

A lamp socket S is mounted in an enlarged hole in the support 3 so as to permit adjustment about a retaining screw 9 held by nuts 10 which also serves as a wire connection terminal. The socket S is held in its adjusted position by a similar screw 11 in the opposite side passing through 110

a slot in the support 3 and held by an insulating knurled nut 12.

The socket S carries a suitable electric lamp E of the concentrated filament type which is to be located by adjusting the socket with the means previously described so that its filament or point source of light is at the focus of the lens combination.

The hollow frame portion F¹, which is best shown in Fig. 3, has two openings 13 and 14 spaced substantially at right angles on surfaces each facing the lamp E. A plate P, having a small center light aperture, is provided to cover each of these openings and emit a small beam 15 of light into the hollow of the frame portion F¹.

The plate P is shown in detail in Fig. 5 and contains slots at each end which fit loosely on the body of two retaining screws 15 which are tapped into the hollow frame portion F¹ and have enlarged heads bearing on washers 17. This permits a slight shifting of the plate P in any direction on the surface of the hollow frame portion F¹ and the frame openings 13 and 14 are large enough not to interfere with the passage of light through the light apertures of the plates P in any adjusted position.

The rear of the hollow frame portion F¹ holds a rear light shield 19 and a cover 20 by two screws 21 and 22. Between these two members covering the end of the hollow frame portion F¹ is a translucent sheet 23 having intersecting cross lines at each end thereof which intersect at a point substantially in alignment with each light aperture of the plates P and the filament of the lamp E.

The rear light shield 19 and the cover 20 each has two windows W¹ and W² which are concentrically located about each of the aforesaid cross lines of the translucent sheet 23. When the unit is now assembled and the lamp E properly located and energized as previously described, the plates P are adjusted so that the two beams of light emitted into the hollow of the frame portion F¹ by the light apertures thereof strikes the intersection of the cross lines at window W¹ and W².

Two terminals 24 and 25 are mounted in the frame portion F¹ through suitable insulating bushings 26 which carry short flexible connecting wires to the socket S and are included to facilitate in making external connections to the light projecting unit. The rear of the unit is completely housed by a cover C, and a hood H of conventional design is held over lens L¹ by screws 27.

The unit may be suitably mounted, such as by three studs 28, which are tapped into the frame F and held by pins 29. These studs 28 are shown projecting through a supporting back ground B spaced therefrom by springs 30 and held by nuts 31 and lock nuts 32.

It will now be seen that a light projecting unit has been provided which permits the movement of the lamp socket with respect to the lens in practically any plane, and which permits the socket to be securely clamped in any such position. Inasmuch as compensation for the variation in lamp filament locations is necessary, a further provision has been made to fix two points which gives a permanent alignment of the correct

filament location and to fix a second two points so disposed that they align the correct filament location along the line of the first two points.

The path of the light beams from a correctly positioned filament through the above mentioned fixed points is illustrated by the dotted lines in Fig. 4 and it can readily be seen that any deviation of the filament position in any direction will cause the light beams emitted by the plates P to strike the windows W¹ and W² at points other than the intersection of the cross lines. In this manner, when renewing lamps, an adjustment of the socket can be easily and quickly made so that these light beams strike directly on the intersection of the cross lines at both windows and thus be assured that the intensity of the light from the new lamp is as great as that of the old.

The above rather specific description of one form of the present invention is given solely by the way of example, and is not intended, in any manner whatsoever, in a limiting sense. It is also to be understood that various modifications, adaptations and alterations may be applied to meet the requirements of practice, without in any manner departing from the spirit or scope of the present invention, except as limited by the appended claims.

Having thus described my invention, what I claim is:—

1. In a light signal, in combination, a lens, a 105 light source, a support bracket fixed relatively to the lens, adjustable socket means in the bracket for receiving the light source, two apertured plates, oversized openings in the plates, bolts passing through the openings and into the 110 bracket, for permitting clamping the plates in various adjusted positions on the bracket, the apertures in the plates receiving the direct beams from the light source, and two visible fixed point defining means on the bracket for respectively 115 directly receiving light beams passing through said apertures, when the light source is on focus.

2. In a light signal unit, a frame member, a lens carried by the member, said member having a hollow rearwardly extending portion open 120 at the rear, an opaque member covering the opening at the rear and having two windows therein, point defining means on the windows, two plates, means for securing the plates to said hollow frame portion and including loosely fitting screws passing through apertures in the plates, a perforation in each plate, holes in said hollow frame portion covered by said plates, said plates when in adjusted position allowing the passage of two radial light beams from the light source at the lens 130 focus, upon said point defining means.

3. In a light signal unit, a frame member, a lens in the frame member, a light source support on the frame member, said frame member having a hollow rearwardly extending portion, two 135 spaced translucent screens in the hollow portion, point identifying means on the screens, two apertured plates, and means for fixing the plates in various adjusted positions on the frame member and between the lamp support and the screens, 140 whereby to allow light from the light source when on focus to pass through the apertures and onto the point identifying means on the screens.

OSCAR S. FIELD.
